UNITED STATES PATENT OFFICE.

WINTON E. BROWN AND CHARLES T. BROWN, OF SACRAMENTO, CALIFORNIA.

ATOMIZER.

Application filed May 1, 1922. Serial No. 557,725.

To all whom it may concern:

Be it known that we, WINTON E. BROWN and CHARLES T. BROWN, citizens of the United States, residing at Sacramento, county of Sacramento, and State of California, have invented new and useful Improvements in Atomizers, of which the following is a specification.

This invention relates to atomizers and especially to that type employed in conjunction with spray painting machines.

Most spray painting machines in use today are objectionable for several reasons: First an air pressure ranging from 90 to 125 pounds is usually required, necessitating the use of substantial air and paint containers, together with more or less costly air compressors and heavy pipe fittings; secondly, high air pressure usually limits spray painting to certain classes of work and can by no means be universally employed; third, high pressure is not economical as it wastes power, air and paint, and it is furthermore a source of danger to the health of the workers as the escaping air carries away paint in a highly atomized or foglike condition; and fourth, the cost of the equipment is excessive and weight is such that it becomes cumbersome to handle, etc.

The object of the present invention is to generally improve and simplify paint apparatus as a whole, and especially to provide an atomizer which will efficiently atomize the paint by whirling or centrifugal action, regardless of whether the paint is heavy, light, thin or otherwise, and which will not liberate the paint until it is thoroughly atomized; to provide an atomizer which operates successfully under an air pressure of from 5 to 25 pounds; an atomizer which will eliminate the unhealthy feature of spray painting, and which is not limited to certain fields of application but distinguishes by being universally applicable. Other objects will hereinafter appear.

The invention consists of the parts and the construction, combination and arrangement of parts as hereinafter more fully

described and claimed, having reference to the accompanying drawings, in which— Fig. 1 is a central, vertical, longitudinal section through the atomizer.

Fig. 2 is a section on line 2—2, Fig. 1.

Fig. 3 is a central, vertical, longitudinal section of the atomizer showing a modification of the structure.

Fig. 4 is a view of a streak of paint applied to the surface by a high pressure atomizer.

Fig. 5 is a similar view showing paint applied to the surface by the low pressure atomizer illustrated in this invention.

Referring to the drawings in detail, and particularly to Figs. 1 and 2, A indicates a cylindrical casing which tapers from end to end. Formed in the interior thereof is a cylindrical chamber B which also tapers from end to end. This chamber communicates with a discharge opening 2 formed at the forward end, and it also communicates with an annular mixing chamber 3 formed at the inner end. The annular mixing chamber is separated from the main chamber B by an annular ring-like flange 4. The paint to be atomized is delivered to the annular chamber 3 by means of a passage 5, and the air employed for atomizing purposes is delivered through a passage 6 disposed at a tangent to the annular chamber 3 and substantially at right angles to the passage 5; the passages 5 and 6 being connected with suitable sources of supply hereinafter to be described.

In actual practice it is usual to employ a suitable type of compressor, a container for the reception of the air, and a container for the reception of the paint employed. The atomizer is under certain conditions placed directly on top of the paint container and in other instances it is applied to the end of the hose line, thereby permitting the paint and air to be projected directly against the surface to be covered. The atomizer shown in the present instance may be placed at any point desired, for instance on top of the paint container, at the end of the hose

- line, or at any other point desired. It may furthermore be stated that it may be employed in conjunction with a single or a double line as conditions may demand.
- 5 In actual practice we prefer to place the atomizer as close to the paint container as possible and to connect the hose line with the discharge opening 2. The passage 5 is then connected with the paint container and the 10 passage 6 with the air container or the compressor as conditions may demand. Paint and air will, under such conditions, enter the respective passages and as they are disposed substantially at right angles to each 15 other, an atomizing effect will be obtained at the point 7 where the respective streams meet. The partially combined air and paint will then enter the annular mixing chamber 3 on a tangent and a whirling movement will 20 thus be imparted to the mixture, that is it will travel around and around in the annular passage 3 and cannot discharge therefrom except by passing over the annular flange 4 into the chamber B. This is of 25 great importance as any paint particles which are not thoroughly atomized at the point 7 will whirl around and around in the chamber 3 until thoroughly atomized and they will then pass off with the air over the 30 flange 4 into the chamber B. They will then pass forwardly through this chamber in a thoroughly atomized condition and will finally discharge through the hose line connected at the point 2 and may thus be directed 35 to the surface to be painted or covered. In other words the paint and air is first subjected to an atomizing action at the point 7, and secondly to an atomizing action in the 40 annular chamber 3; the atomizing action in chamber 3 being constant as any paint particles which are not thoroughly atomized at the point 7 will be whirled around and around until completely atomized. The second atomizing action is therefore continuous 45 and as the paint is constantly subjected to the whirling air until completely broken up and atomized, it will be in a condition to pass off with the air and enter chamber B from where it is discharged.
- 50 The atomizer here shown, due to the efficiency of the atomizing arrangement employed, permits the use of low pressure air as distinguished from most equipments now commonly employed, that is air from 5 to 25 pounds pressure will efficiently atomize the paint, whether thick, thin or otherwise, as it is subjected to the whirling action of the air in the annular chamber 3 until it is atomized, and for this reason no unatomized particles of paint can escape. The use 55 of low pressure air eliminates the unhealthy condition usually encountered with high pressure air; it furthermore eliminates waste of both air and paint; it permits the 60 application of a heavier and more uniform coat; and it permits the formation of a clean margin, for instance when applying trimming coats and the like.
- Paint applied by the atomizer here illustrated forms a uniform dense coat with a 70 clean margin as illustrated in Fig. 5, while paint applied by high pressure air leaves a shady margin, which has a tendency to spread, and furthermore a coat which is not as dense as that applied by a low pressure 75 atomizer; the coat applied by high pressure air being illustrated in Fig. 4.
- The cost and operation of a low pressure equipment is low compared with a high pressure equipment as a compressor of smaller 80 capacity can be employed, and similarly lighter fittings and containers for the paint and air respectively. An equipment of this character can therefore be readily handled, while a high pressure equipment becomes 85 cumbersome and unwieldy due to the greater weight, etc.
- While certain features of the present invention are more or less specifically illustrated, we wish it understood that various 90 changes in form and proportion may be resorted to within the scope of the appended claims, similarly that the materials and finish of the several parts employed may be such as the experience and judgment of the manufacturer may dictate or various uses 95 may demand.
- Having thus described our invention, what we claim and desire to secure by Letters Patent is—
1. An atomizing device of the character described comprising an elongated cylindrical casing, a chamber formed in the interior thereof, a discharge opening formed at one end of the casing and in communication with said chamber, an annular mixing chamber formed within the casing disposed at right angles to the longitudinal axis of the casing and the main chamber formed therein, and a liquid and an air inlet passage formed in the casing in communication with the annular chamber and disposed on a tangent with relation thereto.
2. An atomizing device of the character described comprising an elongated cylindrical casing, a chamber formed in the interior thereof, a discharge opening formed at one end of the casing and in communication with said chamber, an annular mixing chamber formed within the casing disposed at right angles to the longitudinal axis of the casing and the main chamber formed therein, and a liquid and an air inlet passage formed in the casing in communication with the annular chamber and disposed on a tangent with relation thereto, and said liquid and air inlet passages being disposed substantially at right angles to each other.
3. An atomizing device of the character described comprising an elongated cylindri-

cal casing, tapering from end to end, a chamber formed therein and tapering from end to end, said chamber terminating in a discharge passage at its smaller end, a 5 mixing chamber, an annular flange formed in the interior of the casing, an annular passage formed rearwardly of the flange and in communication with the main chamber, said annular passage being in communication with an air inlet passage formed 10

in the casing and tangentially disposed with relation to the annular passage, and a liquid supplying passage formed in the casing at substantially right angles to the air inlet passage and communicating 15 with the air passage and the annular passage.
